Primary Examiner — Brett Miller*Assistant Examiner* — Sara Michie Pottenger(74) *Attorney, Agent, or Firm* — Distinct Patent Law;
Justin P. Miller(57) **CLAIM**

The ornamental design for a door jamb, as shown and described.

DESCRIPTION

FIG. 1 is a perspective view of a door jamb showing the new design;

FIG. 2 is a front elevation view thereof;

FIG. 3 is a back elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines are for the purpose of illustrating the unclaimed portions of the article and form no part of the claimed design.

1 Claim, 7 Drawing Sheets(56)
